UNITED STATES PATENT OFFICE

STEWART GILLELAND, OF SEATTLE, WASHINGTON

HOLDER FOR RUBBER STAMPS

Application filed November 16, 1929. Serial No. 407,638.

My invention relates to improvements in holders for rubber stamps of the form commonly used by hand for dating, receipting cancelling and the like and the object of my invention is to provide a holder of simple and compact construction to which a plurality of rubber stamps may be attached and by which said stamps may be held in contact with inking pads and in such positions that they are always readily accessible for use, said holder also embodying means for returning the stamps to the inoperative position in contact with the inking pads as soon as the stamps are released after use.

Other objects are to provide a rubber stamp holder by which the rubber stamps are all held in an upright position when not in use whereby they will occupy a minimum amount of desk space; to provide a holder in which the rubber stamps are mounted on a rotatable frame which may be turned freely to permit a desired stamp to be quickly and easily located; and to provide a holder in which the rubber stamps are pivotally mounted on the ends of arms and are provided with finger pieces by which they may be grasped and turned by a very easy and natural movement of the wrist and forearm as the stamps are brought down onto the paper or article which is being stamped.

Other and more specific objects of the invention will be apparent from the following description taken in connection with the accompanying drawings.

In offices where a number of rubber stamps are used it is common practice to leave these stamps lying on a desk or in a tray, or to hang them on a rack provided for this purpose. When a stamp is to be used the proper stamp must first be located, the operator then picks up the stamp, inks it by pressing it against an ink pad, stamps the paper on which it is to be used and then replaces the stamp. Often the ink pad will have a cover which will have to be opened preparatory to inking the stamp and closed after the stamp has been inked. This necessitates several operations and requires considerable time for each use of the stamp and also makes it possible, where the stamp is kept in a particular location, to put

the stamp back in the wrong place thus making it necessary to search for the stamp the next time it is to be used.

In accordance with my invention I provide a holder of neat appearance and compact construction for holding the rubber stamps in such a manner that they will always be readily accessible to the user and can not be removed from the holding means and will always be automatically inked and will require the least possible number of operations to use and will always be returned to the place where they belong after use.

In the drawings Fig. 1 is a vertical mid section of a rubber stamp holder constructed in accordance with my invention, showing the stamps and stamp arms in a raised position.

Fig. 2 is a fragmentary sectional view of the same, showing one stamp and stamp arm lowered into a stamping position.

Fig. 3 is a plan view of the device with all the stamps and stamp arms raised.

Fig. 4 is a fragmentary sectional view on line 4—4 of Fig. 1 showing one form of pivot means for the bottom ends of the swinging arms.

Fig. 5 is an enlarged section through slot and pin means by which rubber stamp brackets are secured to swinging arms.

Fig. 6 is a fragmentary elevation of a modified form of stamp supporting arm which may be embodied in the invention.

Fig. 7 is a fragmentary section of a modified form of ink pad.

Like reference numerals designate like parts throughout the several views.

Referring to the drawings, I show a stamp holding device embodying a relatively heavy base 7, preferably of lead, secured by screws 7' to a suitable disc or plate 8 which may have a padding 9, as of felt, provided thereon to avoid marring desks and the like on which the device is set. The base 7 is preferably of conical shape and has an axial pivot pin 10 embedded therein and extending upwardly therefrom to form a vertical bearing for an upper rotatable frame or body. Said frame embodies an upper pad holding drum 11 of polygonal shape connected with a portion 12,

which converges downwardly to a location 13 of smaller diameter and then expands to form a hollow cone shaped bottom portion 14 arranged to fit over the heavy base 7. The cone shaped bottom portion 14 preferably terminates at its lower end in a cylindrical portion 15 having bearing brackets 16 provided thereon. A bearing hub 17 is fixedly secured within the smaller portion 13 of the rotatable housing and fits over the pivot pin 10 and means, as a nut 18 is provided for preventing separation of the two housing parts. A rod 20, having a loop 21 on its upper end, may be secured to the pivot 10 to afford convenient means by which the device may be picked up and moved about.

A plurality of arms 22 for holding the stamps are distributed at frequent intervals around the rotatable frame and the bottom end of each of said arms is connected by a pivot pin 23 with one pair of lugs 16. When thus mounted, these arms are free to stand upright alongside of the rotatable frame or to be swung downward in radial paths to a substantially horizontal position. In the drawings I have shown twelve of said stamp carrying arms 22 and have shown the drum 11 to be a polygon of twelve sides, each side forming a flat surface against which an ink pad 24 may rest. It will be understood however, that a greater or less number of arms 22 may be provided, as desired, and that the size of the rotatable frame may be varied to suit the number of stamps which are to be taken care of.

The upper ends of the arms 22 are preferably made tubular for the reception of the cylindrical ends 25 of brackets 26 to which the blocks 27 of rubber stamps may be secured by screws 28. Finger pieces 29 are also secured to, or formed integral with, the brackets 26. Type 30 of the usual form is provided on the blocks 27.

Removal of the cylindrical bracket ends 25 from the tubular ends of the arms 22 is prevented by means of pins 31 which operate in slots 32 in the arms 22. The slots 32 allow the brackets 26 to be turned through an angle of substantially one hundred eighty degrees 50 as the arms are lowered from the position shown in Fig. 1, to the position shown in Fig. 2. A coil torsion spring 33 is provided on each arm 22. Each spring 33 has one end hooked onto the pin 31 and the other end fixedly connected as by a pin 34 with its respective arm 22. The springs 33 return the blocks 27 to the position shown in Fig. 1 as soon as the finger pieces are released after use thus insuring that the type 28 will always rest 60 against the inking pad 24 when the arms 22 are in the upright position. Tension springs 35 serve to keep the arms 22 in the upright position except when they are pressed down for the purpose of stamping. A trough 36 65 may be provided at the lower end of the ink

pad 24 to catch ink if any of such ink should drain out of said pad.

The finger pieces 29 extend outwardly from the brackets 26 as shown and preferably are each provided with two finger holes 37 for convenient reception of the first two fingers of the right hand. By inserting the first two fingers of the right hand in the bracket 26 at the left hand side of the device shown in Fig. 1, with the back of the hand turned toward the drum 11, and then bringing the arm 22 down into the position shown in Fig. 2, allowing a free and natural movement of the arm and wrist as the arm comes down, the stamp clock and bracket 26 will be turned through substantially a complete half turn. After the stamping is done the hand may be allowed to follow the arm back up, the spring 35 draws the arm 22 back to its proper position regardless of where and when it is released, and the torsion spring 33 turns the bracket 26 back so that the type 30 on the block 27 will rest against the ink pad 24.

In the operation of the device the operator first turns the rotatable frame to bring the stamp he wishes to use into position, preferably to the left hand side of the machine. He then grasps the finger piece on the desired stamp, swings the arm 22 down far enough to apply the stamp and lets said arm move back into the upright position again. The stamp blocks 27 or the arms 22 or brackets 26 may be marked to designate the stamp, and a person who uses the stamps frequently will soon learn to locate the desired stamp almost instantly without reading the signs. Rubber stamps of conventional shape and size may be used by cutting off the hand hold portion of the block and securing the type carrying portion of the same to the brackets 26.

My rubber stamp holder is neat and attractive in appearance, cheap and compact in construction, simple and efficient in operation and saves time and labor by reducing the number of operations required for applying a stamp and by affording means to which the stamps may be permanently attached thus compelling an orderly arrangement of the stamps and preventing loss and misplacement of said stamps.

In Fig. 6, I have shown a modified form of stamp carrying arm 38 which is formed in part of a coil 39 of spring wire which normally holds the arm upright and flexes to permit swinging down of the arm and also yields torsionally to allow the necessary turning of the stamp block.

In Fig. 7, I show a fragment of a drum 11 provided with clips 40 for the reception of a separate ink pad 41 for each rubber stamp. This makes it possible to use pads of different colors, as blue and red and black, for different stamps, and also makes it possible to turn the pads end for end if the ink tends to settle to the bottoms of the pads.

The foregoing description and accompanying drawings clearly disclose a preferred embodiment of my invention, but it will be understood that this disclosure is merely illustrative and that changes may be made within the scope and spirit of the following claims.

I claim:

1. A holder for rubber stamps, embodying a plurality of arms pivotally mounted to swing between an upright position of rest and a horizontal stamping position and means for supporting stamps on the outer ends of said arms.

2. A holder for rubber stamps, embodying a plurality of arms pivotally mounted to swing between an upright position of rest and a horizontal stamping position, rubber stamps, and means pivotally connecting said rubber stamps with the outer ends of said arms.

3. A holder for rubber stamps, embodying a frame mounted for rotary movement on a vertical axis, a plurality of arms pivoted at their bottom ends to said frame and rubber stamps connected by pivot means with the upper ends of said arms.

4. A holder for rubber stamps, embodying a frame mounted for rotary movement on a vertical axis, a plurality of arms pivoted at their bottom ends to said frame and arranged to swing from an inoperative upright position to a horizontal stamping position, rubber stamps for the upper ends of said arms and pivotal means connecting said rubber stamps with said arms.

5. A holder for rubber stamps, embodying a frame mounted for rotary movement on a vertical axis, a plurality of arms pivoted at their bottom ends to said frame and arranged to swing from an upright inoperative position to a horizontal stamping position spring means urging said arms upwardly, and rubber stamps connected by pivot means with the upper ends of said arms.

6. A holder for rubber stamps, embodying a frame mounted for rotary movement on a vertical axis, a plurality of arms pivoted at their bottom ends to said frame and arranged to swing from an upright inoperative position to a horizontal stamping position, rubber stamps connected by pivot means with the upper ends of said arms, and ink pad means on the upper part of said frame, against which said rubber stamps may rest when said arms are upright.

7. A holder for rubber stamps, embodying a frame mounted for rotary movement on a vertical axis, a plurality of arms pivoted at their bottom ends to said frame and arranged to swing from an upright inoperative position to a horizontal stamping position, resilient means urging said arms upwardly, rubber stamp brackets extending outwardly from the ends of said arms and pivotally connected axially with said arms, rubber stamps on said

brackets and ink pad means against which said rubber stamps may rest when said arms are in the upright position.

8. A holder for rubber stamps, embodying a frame mounted for rotary movement on a vertical axis, a plurality of arms pivoted at their bottom ends to said frame and arranged to swing from an upright inoperative position to a horizontal stamping position, resilient means urging said arms upwardly, rubber stamp brackets extending outwardly from the ends of said arms and pivotally connected axially with said arms, rubber stamps on said brackets, ink pad means on the upper portion of said frame, springs yieldingly urging said rubber stamps into portions in which they will rest against said ink pad means when said arms are upright and finger hold means by which said rubber stamps may simultaneously be moved down and turned for stamping.

9. In a rubber stamp holder an arm pivoted at its lower end to swing between a vertical and a horizontal position, a bracket axially pivoted to the upper end of said arm, and a rubber stamp secured to said bracket.

10. In a rubber stamp holder an arm pivoted at its lower end to swing between a vertical and a horizontal position, a bracket axially pivoted to the upper end of said arm, means for limiting the rotary movement of said bracket to substantially one half of one complete revolution, spring means tending to rotate said bracket to the limit of its rotary movement in one direction, a rubber stamp secured to said bracket and finger hold means on said bracket by which the same may be grasped to simultaneously lower the arm and turn the bracket in its axial pivot.

11. The apparatus as claimed in claim 10 in which slot and pin means are used to limit turning movement of the bracket on the arm to substantially one half of one complete revolution.

12. In a holder for rubber stamps, a relatively heavy base, an upright frame mounted on said base for rotation about a vertical axis, said frame having a drum at its upper end, ink pads on the exterior of said drum, arms pivoted to the lower end of said rotatable frame, springs urging said arms into upright position, and rubber stamps pivotally mounted on the ends of said arms to engage the ink pads when the arms are raised and to turn face downwardly when the arms are lowered.

13. The apparatus as claimed in claim 12 in which the upright rotatable frame converges below the ink pad drum to form a smaller portion and then expands again to form the base and the springs which urge the arms upwardly are connected with said arms and with the smaller portion of said frame.

14. The apparatus as described in claim 12 in which said base is provided with a bottom

plate which extends beyond its circumference and in which the bottom end of the frame extends downwardly over the base and terminates just above the outwardly projecting edge of said bottom plate.

5 The foregoing specification signed at Seattle, Wash., this 9th day of Nov., 1929.

STEWART GILLELAND.
